LAPPING MACHINE

Herbert S. Indge, Westboro, and Franklin E. Johnson, Worcester, Mass., assignors to Norton Company, Worcester, Mass., a corporation of Massachusetts

Application April 15, 1940, Serial No. 329,592

14 Claims. (Cl. 51—120)

The invention relates to lapping machines, and more particularly to an automatically actuated and controlled lapping machine.

One object of the invention is to provide a simple and thoroughly practical automatic lapping machine. Another object of the invention is to provide a lapping machine in which the approaching movement between the lapping elements is automatically and electrically controlled.

Another object of the invention is to provide an automatic work loading device whereby a plurality of work pieces may be simultaneously moved into and away from an operative position before and after a lapping operation. A further object of the invention is to provide a plurality of work loading devices for simultaneously loading work pieces in a substantially radial direction into an operative position between the lapping wheels.

A further object of the invention is to provide a hydraulically operated control system for moving the upper lapping wheel to and from an operative position and to simultaneously actuate a plurality of work loaders to move work pieces to and from an operative position. A further object of the invention is to provide an electrical control apparatus whereby the cycle of operation may be automatically controlled so that the lapping operation will proceed for a predetermined time interval. A further object of the invention is to provide such an electrical control in which the work loading period is controlled by an electrical control mechanism.

A further object of the invention is to provide a pressure controlling apparatus for automatically controlling the lapping pressure between the lapping wheels and the work to be lapped whereby either a uniform pressure may be obtained during the entire lapping operation or an initial lapping operation at one pressure for a definite time interval, after which the pressure is automatically changed to a second predetermined pressure for a lapping operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of the various possible embodiments of the mechanical features of this invention,

Fig. 1 is a side elevation of the improved lap-

ping machine, having parts broken away and shown in section to more clearly show the construction;

Fig. 2 is a combined diagrammatic showing of the electrical and hydraulic control and actuating system;

Fig. 3 is a fragmentary cross-sectional view through the machine, taken approximately on the line 3—3 of Fig. 1, showing the work loading devices and cage in plan view;

Fig. 4 is a fragmentary sectional view, on an enlarged scale, of one of the work loading units as shown in Fig. 1;

Fig. 5 is a fragmentary sectional view, on an enlarged scale, through one of the work loading devices, taken approximately on the line 5—5 of Fig. 1;

Fig. 6 is a fragmentary sectional view taken approximately on the line 6—6 of Fig. 5;

Fig. 7 is a fragmentary sectional view taken approximately on the line 7—7 of Fig. 6; and

Fig. 8 is a fragmentary sectional view, on an enlarged scale, taken approximately on the line 8—8 of Fig. 1, showing the bracket for supporting the cage.

Referring more particularly to the embodiment illustrated in the drawings, a lapping machine may be constructed in its general aspects similar to the lapping machine illustrated in the prior U. S. Patent to Indge, No. 2,103,984 dated December 28, 1937. This machine, as illustrated, may comprise a base 10 which rotatably supports a lower lapping wheel 11. The base 10 is provided with an upwardly extending column 12 having an outwardly extending horizontal arm 13 which rotatably supports a vertical spindle 14. The spindle 14 carries a rotatable lapping wheel 15 which is connected to the spindle 14 by means of a supporting plate 16.

Power may be obtained from any suitable source, such as an overhead drive shaft or an electric motor mounted on the machine. For the sake of illustration, a belt drive has been shown comprising a driving belt 17 which serves to rotate a pulley 18. The pulley 18 is supported on and arranged to rotate a horizontally extending shaft 19 which is supported in bearings 20, 21, 22 and 23 in the base 10. If desired, a manually operable clutch may be provided similar to that illustrated and described in my prior U. S. patent No. 2,103,984. This feature has not been illustrated in the present case since it is not considered to be a part of the present invention.

The shaft 19 is provided with a worm 25 which meshes with a worm gear 26 mounted on the

lower end of a vertically arranged rotatable shaft 27. The shaft 27 is connected by a universal joint 28 with a shaft 29. The shaft 29 is preferably a telescopic shaft and is connected by a universal joint 30 with a vertical shaft 31. The shaft 31 is supported in bearings 32 and 33 which are in turn supported in a bracket 34 mounted on top of the column 12. The bracket 34 is preferably adjustably mounted on the upper surface of the column 12 and is provided with a screw adjustment comprising a screw 35 which is rotatably supported in a bracket 36 fixed to the upper surface of column 12 and is screw threaded into the bracket 34 so that the bracket 34 may be adjusted transversely relative to the column 12 for the purpose of adjusting the tension of the belt drive to be hereinafter described.

This lapping machine is particularly adapted for the lapping of taper rollers. The lower lapping wheel 11 is provided with a frusto-conical operative face whereas the upper lapping wheel 15 is provided with a plane operative face. The included angle between an element of the operative face of the upper lapping wheel 15 and an element of the frusto-conical operative face of the lower wheel 11 is equal to that of diametrically opposed elements of the conical roller surface to be lapped. In such a machine, it is desirable to impart a rotary motion to the lower lapping wheel 11 which in turn serves as a rotatting and lapping element for a plurality of spaced work pieces. The upper lapping wheel 15 is preferably arranged for a combined rotary and planetary or gyrating movement which engages a plurality of work pieces and in cooperation with the lower lapping wheel 11 serves to lap the conical surfaces of the work pieces to the desired and predetermined extent.

The upper lapping wheel spindle 14 is supported in bearings 37 and 38 which are in turn fixedly mounted in opposite ends of a sleeve 39. The spindle 14 is eccentrically mounted within a rotatable sleeve 40. The sleeve 40 is in turn rotatably supported by bearings 41 and 42 which are carried by a vertically movable sleeve 43. It will be readily apparent from the foregoing disclosure that a rotary motion may be imparted to the spindle 14 and a rotary motion may be simultaneously imparted to the sleeve 40. This combined rotation of the spindle 14 and sleeve 40 serves to impart a combined rotary and planetary or gyrating movement to the upper lapping wheel 15.

The shaft 31 is provided with a multiple V-groove pulley 45 which is connected by V-belts 46 with a multiple V-groove pulley 47. The pulley 47 is fixedly supported on a sleeve 48 which is in turn rotatably supported in a bearing 49 which is carried by the housing 50. The housing 50 also surrounds and supports the vertically movable sleeve 43. The sleeve 48 is connected by relatively long keys 51 with the keyways 52 and 53, respectively, formed in the peripheral surface adjacent to the upper end of the sleeve 40. By means of this splined driving connection, a rotary motion may be imparted to the sleeve 40 while at the same time the sleeve 40 may be moved in a vertical direction by vertically adjusting the sleeve 43.

A pulley 55 is keyed to a reduced upper portion of the pulley 45 and is connected by means of a belt 56 with a pulley 57. The pulley 57 is slidably keyed to an upper reduced splined end portion 58 of the spindle 14. An idler pulley 60 is provided to maintain the driving belt 56 in the

desired driving tension. It will be readily apparent from the foregoing disclosure that the driving belts 46 serve to produce a rotary motion of the sleeve 40 which in turn transmits a planetary or gyrating movement to the upper lapping wheel 15 and at the same time the driving belt 56 imparts a rotary motion to the upper lapping wheel spindle 14 to produce a combined rotary and planetary or gyrating movement of the upper lapping wheel 15 relative to a plurality of work pieces located therebeneath.

It is desirable to provide a counterbalance mechanism for the upper lapping wheel assembly to counterbalance the weight of the upper lapping wheel and its supporting and actuating parts. The vertically movable sleeve 43 is provided with a rack bar which meshes with a gear 66 rotatably supported on a shaft 67. The shaft 67 also supports a sprocket 68 which is connected by a link chain 69 with a counterbalance weight 70 in a manner similar to that shown and described in my prior U. S. Patent No. 2,103,984, to which reference may be had for details of disclosure not contained herein.

A rotary motion is imparted to the lower lapping wheel 11 by means of a driving mechanism connected with the main drive shaft 19. A worm 75 is mounted on the drive shaft 19 and meshes with a worm gear 76 which is mounted on the lower end of a driving sleeve 77. A driving plate or spider 78 is mounted on the upper end of the sleeve 77 and serves as a support for the lower lapping wheel 11. It will be apparent from the foregoing disclosure that when the shaft 19 is rotated, a rotary motion will be imparted through the mechanism just described to rotate the lower lapping wheel 11 and simultaneously therewith a combined rotary and gyrating or planetary movement will be imparted to the upper lapping wheel 15.

In order to limit the relative approaching movement between the lapping elements, a suitable stop mechanism is provided. As illustrated, a stop mechanism is provided comprising a stop abutment 80 which is supported by the housing 50 which is formed integral with the column 12 and horizontal portion 13. A bracket 81 is adjustably supported on the vertically movable sleeve 43. The bracket 81 carries an adjustable stop screw 82 which is arranged to move in the path of the fixed stop 80 to limit the downward movement of the sleeve 43 and thereby limit the approaching movement of the lap 15 relative to the lower lap 11. By adjusting the position of the stop screw 82 relative to the bracket 81 and also by adjusting the position of the bracket 81 relative to the vertically movable sleeve 43, the stopping of the approaching movement of the lapping wheels may be varied as desired to facilitate lapping work pieces to the required extent.

In order to obtain the desired lapping action between the opposed lapping wheels 11 and 15 as the work is moved into operative position therebetween, it is desirable to provide an actuating mechanism for causing the lapping elements to approach and recede from each other either during each lapping operation or to move the lapping elements into a fixed position while work pieces are fed intermittently into the throat formed between the operative faces thereof. In certain operations it is desirable to start the lapping operation at one pressure to cause the rough lapping of the work piece and then to reduce the pressure between the lapping elements for a finish lapping operation.

A fluid pressure mechanism is provided for causing a relative approaching and receding movement between the lapping elements. In order that a uniform pressure be applied to the upper lapping elements so that the lapping surface thereof will remain in a plane normal to its axis of rotation, a pair of diametrically opposed fluid pressure cylinders 90 and 91 are mounted in position on diametrically opposite sides of the spindle housing 50. The cylinders 90 and 91 are provided with pistons 92 and 93, respectively. The pistons 91 and 92 are connected by piston rods 94 and 95 with a flanged plate 96 which is mounted on the lower end of the vertically movable sleeve 40. The flanged plate 96 is connected to the lower end of the sleeve 40 adjacent to the mounting plate 16 of the upper lapping wheel 15 so that when pressure is applied to the diametrically arranged pistons, the pressure is uniformly distributed over the entire surface of the upper lapping wheel and there is no tendency on the part of the lap to assume other than a plane normal to its axis of rotation and revolution, thus minimizing any errors in the lapping operation due to lost motion between the lapping wheel 15 and its supporting parts.

Fluid for the pressure system is supplied from a reservoir 100 which is preferably located within the base 10 of the machine. Fluid is conveyed from the reservoir 100 through a pipe 101 by means of a motor driven fluid pressure pump 102 which forces fluid through a pipe 103 to a main control valve 104. The valve 104 is of a balanced piston type comprising a valve stem 105 having formed integrally therewith valve pistons 106, 107 and 108. In the position shown in Fig. 2, fluid under pressure passing through the pipe 103 enters a valve chamber located between the valve pistons 107 and 108 and passes out through a pipe 109 which is connected by pipes 110 and 111 to admit fluid simultaneously to cylinder chambers 112 and 113, respectively. The admission of fluid under pressure to the cylinder chambers 112 and 113 causes a downward movement of the pistons 92 and 93, respectively, to produce a downward approaching movement of the upper lapping wheel 15. During the downward movement of the upper lapping wheel 15, fluid within cylinder chambers 114 and 115, respectively, exhausts through a pipe 116 and out through a valve chamber located between the valve pistons 106 and 107 and passes through a pipe 117 which exhausts into the reservoir 100.

An adjustable pressure relief valve 118 is connected by a pipe 119 with the pressure pipe 103. The relief valve 118 may be adjusted to maintain a desired operating pressure within the fluid system. When pressure within the fluid system increases above the set pressure, the valve 118 opens and passes excess fluid under pressure through an exhaust pipe 120 into the reservoir 100. If desired, a second pressure relief valve 121 may be provided which may be set at a different operating pressure from the valve 118. The valve 121 is connected by a pipe 122 with a manually operable shut-off valve 123 which is in turn connected by means of a pipe 124 with a piston type control valve 125. The control valve 125 is actuated by means of a solenoid 126. In the position of the valve 125 as illustrated, the fluid under pressure passing through the pipe 103 does not enter the valve 125.

If it is desired, a relatively high pressure may be provided at the start of the lapping operation by adjustment of the valve 118. During the

initial lapping operation, the solenoid 126 may be energized to maintain the valve 125 in the position illustrated in Fig. 2. After a predetermined time interval the solenoid 126 may be de-energized, thus connecting the valve 125 with the pressure line 103 which in turn renders the relief valve 121 operative. If the valve 121 is set for a lower operating pressure than the valve 118, then the valve 121 will control the pressure within the fluid system. If preferred, the valves 118 and 121 may be manipulated so that, if desired, the lapping operation may be started at a low pressure and the pressure then increased as the lapping operation proceeds, or a single pressure may be utilized during the entire lapping operation.

The valve 104 may be operated manually by means of a manually operable control lever 130 which is supported on a rock shaft 131. The rock shaft 131 also supports a rock arm 132 which is connected at one end to the valve stem 105 by means of a stud 133. In order to balance the weight of the lever 130 and the valve, a counter-balance weight 134 is connected to the opposite end of the rock arm 132. By adjusting the weight 134, the valve may be balanced so that it may be moved readily manually or electrically. A spring 134 is interposed between a stud projecting from the rock arm 132 and a stud 135 which is fixed to the casing of the valve 104. The spring 134 normally serves to hold the valve 104 in an uppermost position, that is, in a position so that fluid is admitted through the pipe 116 to hold the upper lapping wheel 15 in an uppermost or inoperative position. A push type electrical solenoid 136 is provided to shift the valve stem 105 downwardly at the start of the lapping cycle against the tension of the spring 134 and serves to maintain the valve in this downward position during the lapping cycle so that fluid under pressure is admitted to hold the upper lapping wheel 15 in a downward position (Fig. 2).

An automatically operated work loading mechanism is provided for intermittently and automatically loading work pieces into position between the lapping wheels 11 and 15, respectively. A plurality of work loading devices are arranged about the periphery of the lapping wheels which are arranged in close relationship with each other intermittently to move work pieces in a substantially radial direction into an operative position between the lapping wheels.

A pan-shaped member 140 is mounted on the machine base 10. A plurality of work loading brackets 141 are adjustably mounted on the periphery of the pan-shaped member 140 (Figs. 1 and 5). The work loading brackets 141 are each provided with parallel elongated slots 142 and 143 (Fig. 5). Clamping bolts or screws 144 and 145 pass through the elongated slots 142 and 143, respectively, and are screw threaded into the pan-shaped member 140. By means of this construction, the work loading bracket 141 may be adjusted vertically relative to the pan-shaped member and locked in adjusted position by tightening the screws 144 and 145.

The work loading bracket 141 is provided with a horizontally movable work transfer member or slide 146 which is provided with a clearance aperture therein shaped and arranged to receive a work piece 147 to be lapped and to transfer it from a work hopper or magazine 138 into an operative position between the lapping wheels 11 and 15 (Fig. 1). The slide 146 is preferably moved by means of a hydraulically operated

mechanism comprising a cylinder 148 having a slidably mounted piston 149 contained therein. The piston 149 is connected to one end of the slide or transfer member 146 and serves to move the transfer slide 146 toward the right (Fig. 2) or in a substantially radial direction (Fig. 3) relative to the lapping wheels 11 and 15, respectively. The inner end of the slide 146 is provided with an enlarged trapezoidal-shaped end portion 150 (Fig. 3) having a tapered end portion 151 which mates with a correspondingly shaped aperture 152 formed in a cage member 193.

The cage member 193 is supported by a centrally-located vertically-adjustable rotatable stud 194. The cage member 193, however, is held against rotation by a stop plate 195 which is provided at its inner end with an enlarged shaped end portion which mates with and engages one of the slots or notches 152 formed in the periphery of the cage member 193. The stop plate 195 is adjustably fastened by a bolt or screw 196 on the upper surface of a supporting bracket 197. The stud 194 may be adjusted vertically to position the cage member 193 in the desired position with respect to the operative surfaces of the lapping wheels 11 and 15. The bracket 197 may be adjusted vertically to adjust the position of the stop plate 195 relative to the cage member 193.

The cage member 193 serves to support and steady the inner end of the slide or work transfer member 146 during a lapping operation. The work transfer slide 146 (Fig. 1) is shown in a forward or operative position with a work piece 147 in operative position between the lapping wheels 11 and 15. Each of the work loading brackets 141, 141a, 141b, 141c, 141d, 141e, 141f, 141g, 141h, 141i and 141j is provided with an inclined work discharge chute or passage 155 (Fig. 1) the upper end of which is covered by a slidably mounted member 156. The cover 156 is preferably actuated hydraulically in timed relation with the work transfer slide 146 by means of a cylinder 157 having a piston 158 slidably mounted therein. The piston 158 is connected by means of a piston rod 159 with the slidably mounted cover 156.

When the work transfer slide 146 is moved toward the left (Fig. 1) after a lapping operation has been completed upon the work piece 147, fluid under pressure is admitted to move the cover 156 toward the left (Fig. 2) so that when the work piece 147 moves into alignment with the upper end of the discharge chute or passage 155, it drops therefrom under the influence of gravity and is discharged into a container 139 which is fastened to the work loader bracket 141.

Each of the work loading devices is provided with a control valve 160. The control valve 160 is a piston type control valve comprising a valve stem 161 having formed integrally therewith valve pistons 162, 163 and 164. The valve 160 may be actuated manually, if desired, or automatically by a hydraulically operated mechanism, as shown in Fig. 2.

A work loader control valve 166 is provided which serves simultaneously to operate and control all of the work loader control valves 160 or to cut off fluid under pressure from the end chambers of the valves 160 to render each of the valves 160 operable under manual control. The control valve 166 is mounted on the front of the machine base. The valve 166 is a piston type

valve comprising a valve stem 167 having formed integrally therewith valve pistons 168, 169, 170, 171 and 172. In the position of the valve 166 (Fig. 2), fluid under pressure passing through the pipe 103 enters the valve chamber located between the valve pistons 107 and 108 in the main control valve 104 and passes through a pipe 173, through an adjustable throttle valve 174, and through a chamber located between the valve pistons 168 and 169 in the work loader control valve 166 and passes out through a pipe 175 to convey fluid to an end chamber 176 in each of the work loader valves 160 to cause the valve stems 161 to move toward the right (Fig. 2), that is, in a radial direction toward the lapping wheels 11 and 15 (Fig. 3), all of the valves 160 being simultaneously actuated.

During this shifting movement of the valves 160 toward the right (Fig. 2), fluid within end chambers 177 at the right-hand ends of each of the valves 160 is exhausted through a pipe 178, through a valve chamber located between the valve pistons 169 and 170 of the work loader control valve 166, and through a pipe 179 which exhausts into the valve chamber located between the valve pistons 106 and 107 of the control valve 104, and passes out through the pipe 117 which exhausts into the reservoir 100. It will thus be seen that when the solenoid 136 is energized to push the valve stem 105 downwardly to admit fluid under pressure to cause a downward approaching movement of the upper lapping wheel 15, fluid under pressure is passed through the pipe 175 to shift all of the valves 160 of the work loading devices 141.

As shown in Fig. 2, fluid under pressure passing through the pipe 103 also passes through a pipe 180 which enters a valve chamber located between the valve pistons 162 and 163 of the work loader control valves 160, 160a, 160b, 160c, 160d, 160e, 160f, 160g, 160h, 160i and 160j and passes out through a pipe 181 into cylinder chambers 182 to move the pistons 158, piston rods 159 and cover plates 156 toward the right (Fig. 2) to cover the discharge chute or passages 155. At the same time, fluid under pressure passing through the pipe 181 passes through adjustable throttle valves 184 into cylinder chambers 183 to move the pistons 149 and work transfer slides 146 toward the right into the position illustrated in Figs. 1 and 2, which movement transfers a work piece 147 from the hopper or magazine 138 toward the right into an operative position (Fig. 1) between the lapping wheels 11 and 15, respectively. By adjusting the valves 184, the passage of fluid under pressure into the chambers 183 of the cylinders 148 and 148a to 148j inclusive may be varied as desired so that the pistons 158 actuating the cover plates 156 are moved to cover the discharge chutes 155 before the work transfer slides 146 move the work piece 147 across the aperture at the upper end of the discharge chutes 155.

During the movement of the pistons 149 and 158 toward the right (Fig. 2), fluid is exhausted from cylinder chambers 185 in the cylinders 157 through pipes 186 and is also exhausted from cylinder chambers 187 in the cylinders 148 through pipes 188 into common exhaust pipes 189 which pass exhaust fluid through a valve chamber located between the valve pistons 163 and 164 in the control valve 166 and pass the exhaust fluid through a pipe 190 into the exhaust pipe 117 which exhausts the fluid into the reservoir 100.

Each of the plurality of work loading devices

141 and the hydraulic mechanisms for actuating the same are identical in construction, consequently only one of these mechanisms has been described in detail. All of the hydraulic control mechanism, however, is diagrammatically illustrated (Fig. 2) and corresponding parts are designated by the corresponding numerals suffixed with the letters *a*, *b*, *c*, *d*, *e*, *f*, *g*, *h*, *i*, and *j*. It will be readily apparent from the foregoing disclosure that when fluid is admitted through the pipe 175, it will simultaneously be admitted into the end chambers 176, 176a, 176b, 176c, 176d, 176e, 176f, 176g, 176h, 176i and 176j to shift the valves 160, 160a, 160b, 160c, 160d, 160e, 160f, 160g, 160h, 160i and 160j toward the right into the positions indicated in Fig. 2. In this position of the valves, fluid under pressure passing through the pipe 180 is admitted to the left-hand end chambers of the cylinders 148 and 157, respectively, of each of the work loading devices simultaneously to shift the cover plates 156 toward the right to cover the discharge chutes 155 and at the same time move the work transfer slides 146, 146a, 146b, 146c, 146d, 146e, 146f, 146g, 146h, 146i and 146j toward the right (Fig. 2), that is, in a radial direction (Fig. 3) to transfer new work pieces 147 from the hoppers 138 into an operative position between the lapping wheels 11 and 15.

Similarly, when the main control valve 104 is shifted upwardly under the influence of the spring 134 when the solenoid 136 is deenergized, the direction of flow of fluid under pressure is reversed and fluid under pressure passes through the pipe 179 through the valve chamber located between the valve pistons 169 and 170 of the valve 166, through the pipe 178 and simultaneously enters the right-hand end chamber of the work loader valves 160, 160a, 160b, 160c, 160d, 160e, 160f, 160g, 160h, 160i and 160j simultaneously to move the valves toward the left (Fig. 2). This movement of the valves 160 serves to admit fluid under pressure through the pipes 189, 189a, 189b, 189c, 189d, 189e, 189f, 189g, 189h, 189i and 189j to move the work transfer slides 146 toward the left (Fig. 2) that is, in a radial direction (Fig. 3) to remove the work pieces from an operative position between the lapping wheels 11 and 15, respectively. At the same time, fluid under pressure is simultaneously admitted to the cylinders 157 to move the cover plates 156 toward the left to uncover the discharge chutes 155. Due to the adjustment of the throttle valves 184, the speed of movement of the work transfer slide 146 may be adjusted as desired so that the cover plates 156 will move more rapidly to uncover the discharge chutes 155 before the lapped work pieces 147 move into alignment with the discharge chutes 155. When the work transfer slides 146 move the work pieces 147 into alignment with the discharge chute 155, the work piece drops into the discharge chutes 155 and slides into the containers 139. The work transfer slides 146 continue their movement toward the left (Fig. 2), that is, in an outward radial direction (Fig. 3) until the work receiving aperture in the work transfer slides 146 is aligned with the column of work pieces 147 positioned in the work hopper or magazines 138. A new work piece 147 then drops into operative position in the work receiving aperture of the work transfer slide 146 ready for the next loading operation.

In case it is desired to operate the work loading devices 141 manually and individually, the work loader control valve 166 may be shifted toward the left (Fig. 2), which movement opens both

the right and left-hand end chambers of the work loader valves 160, 160a, 160b, 160c, 160d, 160e, 160f, 160g, 160h, 160i and 160j to the exhaust pipe line so that all of these control valves may be manually and independently actuated to control the work transfer slides 146 governed thereby.

It is desirable to provide an automatic cycle control mechanism whereby the approaching movement of the lapping wheels 11 and 15 together with the movement of the work loading devices and the pressure control for the lapping operation may be automatically controlled to produce a predetermined lapping operation. The main control valve 104 is normally held in its uppermost position by means of a tension spring 134. An electrical control apparatus is provided comprising a push button 200 (Fig. 2) which serves to start the lapping cycle. When the push button 200 is closed, it closes a circuit setting in motion an adjustable electrical time relay 201 which may be any of the standard well-known relays, such as that known as the "Microflex" manufactured by Eagle Signal Corporation of Moline, Illinois. Simultaneously with the starting of the relay 201, the solenoid 136 is energized to push the valve stem 105 downwardly into the position shown in Fig. 2. The time relay 201 serves to control the overall lapping cycle and the solenoid 136 remains energized until the time relay 201 operates again to deenergize it at the end of a predetermined lapping cycle.

A similar "Microflex" electrical time relay 202 is provided. This relay is operatively connected to be set in motion when the push button 200 is closed and the relay 201 is started. When the time relay 202 is set in motion, it energizes the solenoid 126 to shift the valve 125 into the position illustrated in Fig. 2, so that the lapping operation proceeds initially at a relatively high pressure as controlled by the pressure relief valve 118. After a predetermined time interval during which the work pieces are lapped while the lapping wheel 15 is held in contact therewith by a pressure as controlled by relief valve 118, the time relay 202 operates to deenergize the solenoid 126 so that the released compression of the spring within the valve 125 moves it toward the right (Fig. 2), thus allowing fluid under pressure to pass through the pipe 124, manually operable valve 123 and pipe 122 through the relief valve 121 which may be set for a lower pressure than valve 118 which governs the lapping pressure for the remainder of the lapping cycle.

When the cycle of operation is started by the closing of the push button switch 200, a relay 203 is energized to break a circuit so as to render a "Microflex" electric time relay 204 inoperative. After the lapping operation has continued for a predetermined time interval as governed by the time relay 201, a circuit is broken, thus deenergizing the solenoid 136 so as to release the tension of the spring 134 which returns the valve 104 to its uppermost position, thus raising the upper lapping wheel assembly and at the same time admitting fluid under pressure to the work loading devices 141 above described simultaneously to move all of the lapped pieces of work in a radial direction (Fig. 3) and to discharge them through the discharge chute 155.

The time relays 201, 202 and 204 are all of the adjustable automatic reset type, such as the "Microflex," or any of the other standard well known types.

When the electric time relay 201 trips at the

end of the lapping cycle, the relay 203 is de-energized which serves to make a circuit and thereby set the time relay 204 in operation. The adjustable time relay 204 is set for a predetermined time interval sufficient to allow the work loading devices to operate, namely to unload the lapped pieces of work and to pick up a fresh piece of work from the work hoppers or magazines 138 and to move them into an operative position. When the time relay 204 trips, it serves again to set in motion the time relays 201 and 203 automatically to start the next lapping cycle. By adjusting the time relay 204, the time interval required for unloading and loading of work pieces may be readily adjusted as desired. It will be readily apparent from the foregoing disclosure that by closing the push button switch 200, the lapping cycle may be started to lap first one batch of work pieces 147 which are then automatically ejected and a fresh batch of work pieces 147 are automatically presented and the next cycle automatically continues. This automatic continuous cycle continues to function until the machine is stopped by the operator.

When it is desired to stop the lapping cycle, the operator pushes a push button 205 which serves immediately to stop the lapping cycle and to return the parts to their inoperative positions. A manually operable switch 206 is provided whereby the relay 202 may be rendered inoperative so that by closing the manually operable valve 123, the entire lapping cycle may be carried on at one pressure as governed by the throttle valve 118 or, if the manually operable valve 123 remains open, then the entire lapping pressure during the cycle of operation will be governed by the pressure relief valve 121.

A manually operable switch 207 is provided for rendering the time relay 204 inoperative, thus making a semi-automatic cycle which is controlled by the push button 200. If the semi-automatic cycle is employed, the work pieces are loaded into position, the lap moves downwardly, and the lapping operation continues for a predetermined time interval after which the cycle stops and the laps separate. Before the next operation may be started, the operator must close the push button switch 200.

A manually operable switch 208 is provided for rendering the entire automatic cycle inoperative, thus cutting out relays 201, 202 and 204. When the switch 208 is opened, the machine may be manually controlled by means of the manually operable control lever 130 which controls the shifting of the main control valve 104. A normally open switch 209 is provided so that when the switch 208 is opened, the switch 209 may be closed to energize the solenoid 136 manually when desired to start and stop a manually controlled cycle, thus obviating the necessity of actuation of the control lever 130.

If desired, the upper lapping wheel 15 may be moved downwardly into a fixed position with the stop screw 82 in engagement with the stop 80, thus positioning the lapping wheel 15 relative to the lapping wheel 11. The lapping wheels 11 and 15 may be maintained in this position while the work pieces 147 are fed in an axial or radial direction into the throat between the two lapping wheels and the desired lapping action may be obtained by this axial feeding component. If the machine is operated in this manner, the speed of movement of the work pieces, that is, the speed of movement of the work transfer

members 146 may be regulated by the adjustable throttle valve 184 to obtain the desired slow rate of feed. The work is finished and sized as desired by the accurate positioning of the upper lapping wheel 15. In order to operate the machine in this manner, a manually operable valve 210 is provided. When the valve 210 is moved toward the left (Fig. 2), it cuts off pressure and exhaust from the pipes 109 and 116 and fluid under pressure may by-pass through a pipe 211 which connects between the pipe line 103 and the valve 210 with the pipe 109 so that a pressure may be provided to hold the upper lapping wheel 15 in a downward direction with the stop screw 82 in rigid engagement with the stop 80 during the lapping operation. In this position of the parts, the actuation of the main control valve 104 operates to control the actuation of the work loading devices only as governed by the electric time relay 201 so that work pieces are intermittently and automatically fed in a substantial axial direction into a fixed grinding throat between the lapping wheels to produce the desired lapping operation and are then automatically ejected from the machine.

The operation of this improved lapping machine will be readily apparent from the foregoing disclosure. Assuming all the parts to have been previously adjusted and all of the hoppers or work magazines 138, 138a, 138b, 138c, 138d, 138e, 138f, 138g, 138h, 138i and 138j are loaded with work pieces 147, power is applied to the driving belt 17 to set the lower lap 11 in rotation and to rotate and planetarily move the upper lapping wheel 15. Assuming the electrical control apparatus is set for an automatic continuous cycle of operation, the cycle of lapping may be started by manually closing the push button switch 200 which, as above described, sets the electric time relays 201 and 202 in operation and at the same time energizes the solenoid 136 to shift the valve 104 in a downward direction so as to admit fluid under pressure to cause the upper lapping wheel 15 to move downwardly into an operative position and at the same time admit fluid under pressure to the work loading devices to shift the work transfer slides so as to present a plurality of work pieces 147 simultaneously into an operative position between the lapping wheels 11 and 15.

The lapping operation continues for a predetermined time interval as determined by the setting of the time relay 201. After the lapping operation has proceeded for the definite time interval, the tripping of the relay 201 deenergizes the solenoid 136 to allow the released tension of the spring 134 to return the valve 104 in an upward direction to again raise the upper lapping wheel 15 and to admit fluid under pressure to the work loading devices to remove the lapped work pieces from an operative position and to allow them to be ejected or discharged through the passages 185. If during this operation the switch 206 is closed, thus rendering the electric time relay 202 operative, this relay is set in motion simultaneously with the relay 201 and serves to control the valve 125 so that for an initial predetermined period, the upper lapping wheel 15 will engage the work at one pressure as governed by the relief valve 118, after which the pressure is automatically reduced and controlled by the relief valve 121.

If the machine is set for an automatic continuous cycle of operation, the relay 203 is energized instantaneously with the setting in motion of the time relays 201 and 202. At the end of

the lapping cycle, the tripping of the relay 201 serves to deenergize the solenoid 136, as above described, and also to deenergize the relay 203 which makes a circuit to set the time relay 204 in motion. The relay 204 is set for a predetermined time interval to govern the unloading and loading time, so that a sufficient time interval is provided for the work pieces to be simultaneously withdrawn and discharged and new work pieces to be presented into an operative position between the lapping wheels 11 and 15.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a lapping machine having a base, a pair of opposed relatively rotatable lapping wheels, means relatively to rotate said wheels, means to cause a relative approaching and receding movement between said lapping wheels, an adjustable stop to limit the approaching movement of said wheels, and a plurality of work loading devices, each comprising a work magazine, a reciprocable work transfer slide to convey work pieces from the magazine into an operative position for a lapping operation and to convey work pieces therefrom after a lapping operation.

2. In a lapping machine having a base, a pair of opposed, relatively rotatable lapping wheels, means relatively to rotate said wheels, means to revolve at least one of said wheels in an orbital path, means to cause a relative approaching and receding movement between said lapping wheels, a work steadyng cage having a plurality of slots formed in its periphery, an adjustable stop to limit the approaching movement of said wheels, and a plurality of work loading devices one opposite each of the slots in said cage, each comprising a magazine or hopper, a reciprocable work transfer slide to convey work pieces from the hopper into an operative position, a shaped end on said slide to mate with a slot in said cage whereby the cage serves to steady the slide and work piece, and a fluid pressure mechanism including a piston and cylinder operatively connected to actuate said slide.

3. In a lapping machine having a base, a pair of opposed, relatively rotatable lapping wheels, means relatively to rotate said wheels, means including a piston and cylinder to cause a relative approaching and receding movement between said lapping wheels, an adjustable stop to limit said approaching movement, a plurality of work loading devices arranged about the periphery of said wheels, each comprising a work magazine or hopper, a reciprocable work transfer slide to convey work pieces from the hopper to an operative position between said lapping wheels, means including a piston and cylinder operatively connected to actuate said slide, and a main control valve simultaneously to control the admission of fluid to the lap approaching cylinders and to all of said work loader cylinders.

4. In a lapping machine having a base, a pair of opposed relatively rotatable lapping wheels having plane operative faces, means relatively to rotate said wheels, means including a piston

and cylinder to cause a relative approaching movement between said wheels, means to limit said approaching movement to provide a predetermined lapping throat, and a plurality of work loading devices arranged about the periphery of said wheels, each comprising a work magazine or hopper, and a work transfer member intermittently to convey work pieces from said hopper in the lapping throat.

5. In a lapping machine having a base, a pair of opposed relatively rotatable lapping wheels having plane operative faces, means relatively to rotate said wheels, means including a piston and cylinder to cause a relative approaching movement between said wheels, means to limit said approaching movement to provide a predetermined lapping throat, and a plurality of work loading devices arranged about the periphery of said wheels, each comprising a work magazine or hopper, a work transfer member on each of said devices, and automatically operated mechanism to move said member automatically to feed work pieces from said hopper into the lapping throat to lap the work to a predetermined extent.

6. In a lapping machine having a base, a pair of opposed relatively rotatable lapping wheels, means relatively to rotate said wheels, means including a piston and cylinder to cause a relative approaching and receding movement between said wheels, a work loading device, means including a piston and cylinder on said work loading device operatively connected to present work pieces intermittently into operative relation with the grinding wheels, a reversing valve for said latter cylinder, said reversing valve having end chambers whereby it is automatically shifted by fluid under pressure, and a main control valve simultaneously to admit fluid under pressure to cause an approaching movement of said lapping wheel and to admit fluid under pressure to one of the end chambers to shift said reversing valve and to control the admission of fluid under pressure to the work loader

45 cylinder automatically to transfer a work piece into operative position between said lapping wheels as the lapping wheels approach each other to produce a predetermined lapping operation.

7. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable transversely movable work transfer slide, the inner end of said slide being shaped to engage a notch in said cage when the slide is in an operative position, and means to reciprocate the work transfer slide automatically and intermittently to transfer a work piece from said hopper into an operative position.

8. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which

includes a work hopper, a reciprocable transversely movable work transfer slide, the inner end of said slide being shaped to engage a notch in said cage when the slide is in an operative position, and means including a piston and cylinder to reciprocate the work slide automatically and intermittently to transfer work pieces from said hopper into an operative position.

9. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable transversely movable work transfer slide, the inner end of said slide being shaped to engage a notch in said cage when the slide is in an operative position, and means including a piston and cylinder on each of said loading devices to reciprocate the work transfer slide automatically and intermittently to transfer work pieces from said hopper into an operative position.

10. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable transversely movable work transfer slide including a clearance aperture therein shaped to receive a work piece, and means including a piston and cylinder on each of said loading devices to reciprocate the work transfer slide intermittently to transfer work pieces into and away from an operative position between said lapping wheels.

11. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable work transfer slide having a clearance aperture shaped to receive a work piece, means including a piston and cylinder on each of said loading devices to reciprocate the slide intermittently to transfer work pieces into and away from an operative position between said wheels, and a fluid pressure system including a main control valve operatively connected simultaneously to control the admission to and exhaust of fluid from all of said loading device cylinders.

12. In a lapping machine having a base, a pair of opposed relatively rotatable lapping wheels, means relatively to rotate said wheels, means to cause a relative approaching and re-

ceding movement between said lapping wheels, a non-rotatable work steadyng cage having a plurality of shaped notches in its periphery, and a plurality of work loading devices spaced around the periphery of said lapping wheels each of which includes a work hopper, a reciprocable transversely movable work transfer slide having a clearance aperture therein shaped to receive a work piece, the inner end of each of said slides being shaped to engage one of the notches in said cage when the slides are in an operative position, and means including a control valve simultaneously to control the admission to and exhaust of fluid from all of the work loading cylinders.

13. In a lapping machine having a base, a pair of opposed relatively rotatable lapping wheels means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable work transfer slide having a clearance aperture therein shaped to receive a work piece, a work discharge chute, a slide adjacent to and below said work transfer slide normally to cover said discharge chute, a piston and cylinder operatively connected to move said work transfer slide intermittently to transfer work pieces from said hopper into an operative position between said wheels, a second piston and cylinder operatively connected to move said work supporting slide on the withdrawal stroke of the work piece to allow the work piece to drop into the discharge chute.

14. In a lapping machine having a base, a pair of opposed relatively rotatable lapping wheels, means relatively to rotate said wheels, means to cause a relative approaching and receding movement between said lapping wheels, a non-rotatable work steadyng cage having a plurality of shaped notches in its periphery, and a plurality of work loading devices spaced around the periphery of said lapping wheels each of which includes a work hopper, a reciprocable work transfer slide having a clearance aperture therein shaped to receive a work piece, means including a piston and cylinder to reciprocate said slide intermittently to transfer work pieces from said hopper into an operative position between the lapping wheels, a work discharge passage, a slide normally covering said passage, and an independent piston and cylinder mechanism to move said work supporting slide, and a fluid pressure control system including a valve for controlling the rate of movement of the transfer slide so that the movement of the transfer slide may be retarded so that the work supporting slide moves ahead of the transfer slide to insure support of the work piece during its in movement and to withdraw the support on the return stroke after a lapping operation to allow the work piece to drop into the discharge passage.
